(57) CLAIM

The ornamental design for a drawer pull, as shown and described.

DESCRIPTION

FIG. 1 is a perspective view of a drawer pull showing my new design;

FIG. 2 is a side elevational view, the opposite side being a mirror image thereof;

FIG. 3 is a front elevational view thereof; and,

FIG. 4 is a top view thereof.

The views of the drawer pull not shown form no part of the claimed design.
